UNITED STATES PATENT OFFICE.

ARTHUR TREVOR DAWSON AND GEORGE THOMAS BUCKHAM, OF LONDON, ENGLAND, ASSIGNEES TO THE VICKERS, SONS & MAXIM, LIMITED, OF SHEFFIELD, ENGLAND.

APPARATUS FOR RUNNING GUNS IN OR OUT ON SHIPBOARD.

SPECIFICATION forming part of Letters Patent No. 615,959, dated December 13, 1898.

Application filed May 16, 1898. Serial No. 680,833. (No model.)

To all whom it may concern:

Be it known that we, ARTHUR TREVOR DAWSON and GEORGE THOMAS BUCKHAM, citizens of England, residing at No. 28 Victoria street, 5 Westminster, London, England, have invented a certain new and useful Apparatus for Running Guns In or Out on Shipboard, (for which we have applied for a patent in Great Britain, dated October 20, 1897, No. 24,263,) 10 of which the following is a specification.

Our invention relates to means for running a gun inboard when required and out again into position for action. For this purpose we mount at the side of the vessel mounting or 15 turret just under the gun one or more rollers, on which the body of the gun can rest, and under the rear part of the gun we run a cradle-truck which can move along a track on the deck or floor and which is provided with 20 winch-gear and a pinion gearing with a rack on the deck or floor. On moving the bushings of the trunnion-bearings so as to present a rearward passage for the trunnions in the known manner, and on slightly raising the 25 breech of the gun by a screw-plunger on the truck the winch is worked so as to run back the cradle-truck, carrying the rear part of the gun, its front part running on the rollers above mentioned, while the mounting of the 30 gun remains stationary. For running the gun out again the winch is worked in the reverse direction, moving the cradle-truck and gun until the trunnions are again engaged in their bearings, in which they are secured, and 35 thereupon the gun is released from the cradle-truck, which is run back, leaving the gun on its mounting.

Figure 1 of the accompanying drawings is a side view of the gun and cradle-truck, 40 showing the gun run in. Fig. 2 is a plan of the mounting, the track, and the cradle-truck in its rear position. Fig. 3 is an elevation, partly in section; and Fig. 4 is a plan of the screw-plunger on the truck, these figures being 45 drawn to an enlarged scale.

M is the mounting, having bearings for the trunnions T, these bearings being of the known kind that can be turned to such a position as to present gaps through which the

trunnions can pass rearward. On the front 50 of the mounting are mounted a pair of inclined rollers S, on which the body of the gun travels when it is run in or out.

On the deck are fixed rails R and between them a rack R'. On these rails run the four 55 wheels of the cradle-truck C, which has a pinion R², gearing with the rack R'. On the truck is mounted in bearings a shaft A, having at each end fly-wheels A' and winch-handles A², by which it can be turned. On it is 60 a bevel-pinion A³, gearing with a bevel-wheel B' on an inclined shaft B, at the lower end of which is a worm B², gearing with a worm-wheel D' on a counter-shaft D, on which is a pinion D², gearing with the pinion R². On 65 the truck C is fixed a bracket E, having a socket to receive a vertically-sliding plunger P, which is prevented from turning by a feather p, engaged in a groove of the socket. The interior of the plunger is screw-threaded 70 to fit a screw-spindle F, which can be turned in either direction by a ratchet-and-pawl lever G. When it is desired to run in the gun, the trunnion-bearings are put in position to allow the trunnions to pass to the rear. The 75 cradle-truck C is run into position under the breech of the gun. The plunger P is raised by working the pawl-lever G, so as to pass up in front of a bracket which projects down from the breech and to slightly raise the 80 breech, thus taking the weight on the truck. The winch-handles A² are then worked so as to turn the pinion R², causing the cradle-truck to move to the rear, taking with it the gun, the body of which as it retreats bears on the 85 rollers S. In order to hold the gun firmly on the cradle-truck, a band H is passed over the breech and connected to the sides of the truck by rods H', provided with tightening-nuts H². The front parts of the rails R are slightly inclined, so that when the cradle-truck has 90 been run under the breech of the gun the first part of the rearward movement of the truck slightly raises the rear part of the gun and the trunnions, giving them freedom to 95 pass out of their bearings.

Having thus described the nature of this invention and the best means we know for

carrying the same into practical effect, we claim—

Apparatus for running a gun in and out on shipboard, comprising a pair of rails and a rack on deck, a pair of rollers on the gun-mounting, a wheeled cradle-truck on the rails having a plunger engaging in front of a bracket of the gear and pinion gearing with the rack and winch-handles and gear adapted to cause the pinion to revolve and the truck to travel along the rails carrying the breech of the gun while the body of the gun runs on the rollers of the mounting, substantially as described.

In testimony whereof we have hereunto set 15 our hands in presence of two subscribing witnesses.

ARTHUR TREVOR DAWSON.
GEORGE THOMAS BUCKHAM.
